UNITED STATES PATENT OFFICE.

NOYES F. PALMER, OF JAMAICA, NEW YORK.

FOUNTAIN-PEN.

SPECIFICATION forming part of Letters Patent No. 352,564, dated November 16, 1886.

Application filed August 6, 1886. Serial No. 210,177. (No model.)

To all whom it may concern:

Be it known that I, NOYES F. PALMER, of Jamaica, Queens county, State of New York, have invented a new and Improved Fountain-
5 Pen, of which the following specification is a full, clear, and exact description.

This invention relates to an improvement in fountain-pens whereby a double feed—one at bottom and one at top of the pen—is obtained.
10 The invention relates to the various features of improvement, hereinafter more fully described.

In the accompanying drawings, Figure 1 is a vertical longitudinal section of a fountain-
15 pen with my improvement. Fig. 2 is a side view of the same. Fig. 3 is a longitudinal section of the bottom feed-block. Fig. 4 is a top view of the same. Fig. 5 is a cross-section of the same at line *x x*, Fig. 3. Fig. 6 is a top
20 view of the pen-plug. Fig. 7 is a bottom view of pen-plug, pen, and bottom feed. Fig. 8 is a top view of the pen-plug with pen in place. Fig. 9 is a cross-section at line *z z*, Fig. 8.

A represents the usual hollow handle or reservoir to contain the ink, provided at its closed end with the usual nipple, *a*, to receive the cap-piece B when the pen is in use. The opening at the other end of this handle is threaded to receive the hollow upper feed and pen-plug, C. This plug receives the gold or other pen, P, and is provided in its inner cavity with a small shoulder, *s*, for the end of the pen to bear against. By this arrangement the pen, after having been removed, will always find its exact position when again replaced into the plug. This plug C is provided with a long narrow extension-tongue, *d*, lying on the top and projecting some distance over the slit of the pen. Into the central hollow part of this plug C the lower feed-plug, E, is inserted. The end *f* of this feed-plug fits tightly into the central opening of the plug C, and is provided with a central cavity, *g*, and a small channel, *h*, on top connecting with the interior of the reservoir
45 A. This channel *h* connects through an opening, *i*, with the central cavity, *g*, and a corresponding opening, *k*, leads from this central cavity, *g*, downward, and connects there with a channel, *l*, extending from this opening *k* to the end of the feed-plug C. From the circular end *f* of this lower feed-plug, E, extends a pro-

jection and tongue, *e*, fitting against the inside of the pen as close as possible, while the outside of this tongue *e* is tapered off and is extended nearly to the point of the pen. On the inside 55 of this tongue *e*, or the side nearest the pen, a channel, *n*, is made, extending nearly to the extreme point of the tongue, and connected with channel *h* on top of the plug. (See Fig. 4.)

The operation is as follows: The hollow handle or reservoir A is filled with ink, the upper feed-plug, C, screwed into the threaded open end, and the central plug, E, inserted into this plug C, when the pen P is inserted between the plugs C and E till it bears against the shoulder *s*, when the pen will be ready for operation, regulating automatically the flow of ink and air in all cases, whether fine lines or broad heavy lines are to be made. When the pen is pressed upon the paper, capillary attraction and gravity draw the ink from the handle or reservoir, according to the opening of the nibs of the pen. Air flows then through the openings *h* and *i* to the channel *h* freely when the nibs of the pen are spread far apart for very heavy lines or 70 writing, while when the pen-nibs are but slightly opened the air will flow only slowly. In other words, the flow of air will be directly in proportion with the opening of the nibs of the pen. If this would not be so, the ink would 75 flow entirely from the hollow handle whenever the position of the pen was with its point downward. The ink lying in the channel *n* in the tongue *e* close to the point of the pen on the under side allows a ready starting, and after 80 starting, and during heavy-line making and shading, the ink-flow is maintained by the top tongue-extension, *d*, of the upper feed, the ink passing from the channel *n* in the lower tongue through the slit in the pen into the 85 cavity formed between the top of the pen and the under side of the tongue *d*, said tongue being slightly bent upward by the bending of the pen during the operation of writing.

It is well known to those skilled in adjusting 90 this class of pens that only a bottom feed is very troublesome and insufficient in heavy-line writing, for the reason that the pressure upon the pen, and the consequent bending of the same upward, leaves the bottom feed channel 95 inoperative without giving the feed too much vent for the ordinary fine-line writing.

The combination of a bottom feed with a top feed entirely relieves this trouble.

I claim as my invention—

1. In a fountain-pen, the combination of the handle or reservoir A, pen-plug C, pen P, and central plug, E, with a projection or tongue, *d*, attached to the pen-plug C and lying upon the pen over the slit, and a projection or tongue, *e*, lying against the inner side of the pen and extending nearly to the point of the pen, substantially as specified.

2. In a fountain-pen, the combination of the pen-plug C with the hollow central feed-plug, E, provided with a central longitudinal cavity, *g*, and channels *h* and *l*, and with opening *i*, connecting the cavity *g* with the channel *h*, and opening *k*, connecting the cavity *g* with the channel *l*, operating in combination with the pen and ink in the reservoir in the manner substantially as set forth.

3. The combination of pen-plug C, having tongue *d*, with the feed-plug E, provided with tongue *e*, cavity *g*, opening *i*, and channel *h*, and channel *n* on the face of the tongue *e*, and forming a continuation of the channel *h*, substantially as described.

4. In a fountain-pen, the combination of a

pen with a top feed consisting of a tongue attached to the pen-plug and lying upon the pen over the slit, and a bottom feed consisting of a tongue attached to the central hollow feed-plug and extending nearly to the point of the pen, and provided with an ink-channel connected to the central cavity of the plug and to a channel on top of said plug, substantially as 35 and for the purpose specified.

5. In a fountain-pen, the combination, with the plug C, of a hollow central feed-plug, E, provided with a forward-extending tongue, *e*, central cavity, *g*, top channel, *h*, connecting 40 with the ink-reservoir, the opening *k*, and channel *l*, connecting with the outer end of the pen-plug C, substantially as and for the purpose set forth.

6. The combination, in a fountain-pen, of a 45 top feed extending over the top of the slit of the pen, with a bottom feed-plug provided with an ink-duct extending underneath the slit of the pen, substantially as described.

NOYES F. PALMER.
